[57] CLAIM

The ornamental design for a cycle pedal, as shown and described.

DESCRIPTION

FIG. 1 is a top plan view of the cycle pedal showing my new design, the bottom plan view being identical thereto;

FIG. 2 is a front elevational view of the cycle pedal, the rear view being identical thereto;

FIG. 3 is a left-side elevational view of the cycle pedal as shown in FIG. 1;

FIG. 4 is a right-side elevational view thereof; and

FIG. 5 is a sectional view taken along line V—V of FIG. 1, the remaining exposed surfaces being plain and unornamented.
